UNITED STATES PATENT OFFICE.

WILLIAM S. THOMSON, OF PLANTSVILLE, CONNECTICUT, ASSIGNOR TO THE H. D. SMITH AND COMPANY, OF PLANTSVILLE, CONNECTICUT, A CORPORATION.

DESIGN FOR A COLD-CHISEL.

44,646.

Specification for Design.

Patented Sept. 9, 1913.

Application filed May 29, 1911. Serial No. 630,238. Term of patent 14 years.

To all whom it may concern:

Be it known that I, WILLIAM S. THOMSON, a citizen of the United States, residing at Plantsville, in the county of Hartford and State of Connecticut, have invented a new, original, and ornamental Design for Cold-Chisels, of which the following is a specification, reference being had to the accompanying drawing, forming a part thereof, in which—

Figure 1 is a perspective view of a cold chisel, showing my new design. Fig. 2 is a side elevation of the same, on a reduced

scale. Fig. 3 is an end elevation, as viewed from the bit end. Fig. 4 is a sectional view on the line $x-x$ of Fig. 2. Fig. 5 is a similar view on the line $y-y$ of Fig. 2. Fig. 6 is an end elevation as viewed from the hammer head end.

I claim:

The ornamental design for a cold chisel as shown.

WILLIAM S. THOMSON.
